UNITED STATES PATENT OFFICE.

WILLIAM H. SCHMEDLEN, OF COLDWATER, MICHIGAN, ASSIGNOR TO THE COLDWATER ROAD CART COMPANY, OF SAME PLACE.

TWO-WHEELED VEHICLE.

SPECIFICATION forming part of Letters Patent No. 326,595, dated September 22, 1885.

Application filed July 8, 1885. (No model.)

To all whom it may concern:

Be it known that I, WILLIAM H. SCHMEDLEN, a citizen of the United States, residing at Coldwater, in the county of Branch and State of Michigan, have invented certain new and useful Improvements in Devices for Preventing the Slipping of Vehicle-Shafts; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in that class of two-wheeled vehicles in which the shafts are attached directly to a square iron axle, and aims to prevent the slipping of the shafts on the axle.

It consists in the novel combination and arrangements of parts hereinafter described and claimed.

In the drawings, Figure 1 is a perspective view of a two-wheeled vehicle provided with my improvements. Fig. 2 is a front elevation, on an enlarged scale, of the lower end of the shaft and a portion of the axle. Fig. 3 is a side view of the same, partly in section. Fig. 4 is a detail perspective view of the retaining-plate.

Referring to the drawings, A represents the shafts, and B the axle.

The axle is provided on the upper side with a mortise or indentation, into which a lug or spur, D, on the under side of the retaining-plate E enters, as clearly shown in Fig. 3. The retaining-plate E is bent upward at its opposite ends, forming the ears E' E', as shown. The lug or spur D is formed on the under side of the retaining-plate E at its center. The plate is made of such a length that when the ends E' E' are bent up they will fit close to the sides of the shaft, as shown in Fig. 2. The retaining-plate is placed on the axle so that the lug D enters the indentation in the axle, and is turned so that the line of direction

of its length will be parallel to the line of direction of the length of the axle.

The end of the shaft is placed on the retaining-plate between the ears E' E', as shown. Two metal straps, F F', are secured to the front and rear sides, respectively, of the shaft, and extend down below the axle, as shown. The lower ends of these straps are rounded and screw-threaded, as shown.

A shaft-brace, G, is secured to the shaft in any desired manner, and extended downward and backward to the lower side of the axle, where it is flattened, forming a clamping-plate, G', and provided with two holes, through which the rounded ends of the straps F F' are inserted.

Nuts H H are placed on the ends of the straps F F', below the flattened portion G' of the shaft-brace, and are turned up against the same to clamp the parts securely together.

It will be readily appreciated that by the construction and arrangement of parts just described the shaft is securely held from slipping on the axle, and the two shafts will be always kept the proper distance apart.

Having thus described my invention, what I claim, and desire to secure by Letters Patent, is—

The combination of the axle provided on its upper side with an indentation, a retaining-plate provided with a lug on its under side to engage the indentation in the axle, and having its ends bent upward at right angles to embrace the shaft, the shaft placed on the retaining-plate, the metal straps secured to the shaft on opposite sides of the same and depending below the axle, their lower ends being rounded and screw-threaded, the axle-brace provided with a flattened portion adapted to serve as a clamping-plate, and the clamping-nuts, substantially as described and shown.

In testimony whereof I affix my signature in presence of two witnesses.

WILLIAM H. SCHMEDLEN.
